BEAUTY KIT

Florence Freiberg, Los Angeles, Calif.

Application June 4, 1947, Serial No. 752,497

2 Claims. (Cl. 132—79)

1

The present invention relates to beauty kits in general and particularly to an improved beauty kit having two compartments and which is particularly adapted to be carried in a lady's pocketbook. Specifically the invention comprises a beauty kit including a base removably seating a plurality of feminine accessories, a central compartment containing powder, and a pivoted cover.

The modern woman's beauty accessories comprising the usual compact, lipstick, rouge and mascara unit are considered by her to be necessary to her well being and comfort. She usually carries these loosely as individual units in her pocketbook where frequently they open, spilling the contents. A plurality of such individual units occupy an unnecessarily large space and frequently become so arranged within the bag as to distort its normal pleasing contours.

The present invention is directed to an improved beauty kit which incorporates in one unit the usual compact and also means incorporating the various other items which the owner may need. The construction is arranged as to occupy a minimum of space and is adapted to be opened selectively to enable the owner to use the compact or other of the contained articles, a mirror being available at all times in which to view her handiwork.

It is, accordingly, an object of the present invention to provide a new and improved lady's beauty kit.

It is another object of the invention to provide a unitary beauty kit incorporating in a plurality of compartments the feminine accessories which are usually found separately.

It is a further object of the invention to provide an improved beauty kit in which a compact may be opened to present simultaneously to the owner the usual puff, powder and a reflecting mirror.

Still another object of the invention is to provide a unitary beauty kit in which, in addition to the usual compact, is a compartment housing a plurality of separately usable feminine accessories, a reflecting mirror being available when such articles are used.

These and other more specific objects will appear upon reading the following specification and claims and upon considering in connection therewith the attached drawing to which they relate.

Referring now to the drawing in which a presently preferred embodiment of the invention is illustrated:

Figure 1 is a top plan view of the beauty kit constructed in accordance with the present invention with certain parts broken away in order better to illustrate the interior construction;

Figure 2 is a transverse medial section upon the line 2—2 of Figure 1;

Figure 3 is a partial section upon the line 3—3 of Figure 1;

Figure 4 is a partial section upon the line 4—4 of Figure 1;

Figure 5 is a partial end view looking in the direction of the arrows upon the line 5—5 of Figure 2 and illustrates the hinge mounting of the parts making up the kit; and

Figure 6 is a partial side view looking in the direction of the arrows upon the line 6—6 of Figure 2 and shows the latch means.

Referring again to the drawing, the unit constructed in accordance with the present invention is indicated generally by the reference character 10 and is seen to comprise a base 11, a central partition 12, and a lid or cover 13. Partition 12 is pivotally mounted to the base and the cover to the partition, as will be described.

Referring first to the base 11, that member is

preferably formed solid of a material such as a molded plastic and has appreciable mass. It is provided at its lower edge with a circumferentially extended marginal rim 16, and with an enclosing upstanding wall 17 which forms a central body cavity. Molded integrally into base 11 are a plurality of receptacles indicated generally by the reference characters 21, 22 and 23, which are, respectively, shaped as to receive a lipstick 26, to serve as a rouge box 27 and as a mascara unit 28. Each of these receptacles is formed with a peripheral enclosing wall and in the case of units 27 and 28 a removable cover is provided, indicated by the reference character of the unit supplemented by a suffix "a." In the case of mascara unit 28 a central wall 28b divides the receptacle longitudinally into a container for a body of mascara 29, and into a pocket for the related brush indicated at 31.

Rouge unit 27 contains a body of rouge 32, and the removable cover 27a normally retains a puff 33 in place upon the rouge.

Intermediate partition 12 is provided with a depending wall 37 designed as to telescope upstanding wall 17 of base 11, and is, upon its upper surface, centrally recessed to provide a shallow cup or receptacle 39, adapted to seat the usual powder retaining pad 41 and an overlying puff 42. Lid or cover 13 is slightly convex and its peripheral rim 44 engages the shouldered upper edge of intermediate member 12, so that it is retained frictionally in its closed position, as illustrated in Figure 2.

The undersides of both partition 12 and cover 13 carry reflecting mirrors, indicated by the reference characters 12b and 13b, respectively, and each is pivoted to the underlying element.

In the case of partition 12 a hinge pin 47 extends between abutments 49 on the wall 17 which at their upper ends extend into spaced recesses 48 in wall 37. The lower edge 51 of the wall 37 between abutments 49 is flattened and is so dimensioned as to abut the adjacent face of wall

2

Figure 4 is a partial section upon the line 4—4 of Figure 1;

Figure 5 is a partial end view looking in the direction of the arrows upon the line 5—5 of Figure 2 and illustrates the hinge mounting of the parts making up the kit; and

Figure 6 is a partial side view looking in the direction of the arrows upon the line 6—6 of Figure 2 and shows the latch means.

Referring again to the drawing, the unit constructed in accordance with the present invention is indicated generally by the reference character 10 and is seen to comprise a base 11, a central partition 12, and a lid or cover 13. Partition 12 is pivotally mounted to the base and the cover to the partition, as will be described.

Referring first to the base 11, that member is

preferably formed solid of a material such as a molded plastic and has appreciable mass. It is provided at its lower edge with a circumferentially extended marginal rim 16, and with an enclosing upstanding wall 17 which forms a central body cavity. Molded integrally into base 11 are a plurality of receptacles indicated generally by the reference characters 21, 22 and 23, which are, respectively, shaped as to receive a lipstick 26, to serve as a rouge box 27 and as a mascara unit 28. Each of these receptacles is formed with a peripheral enclosing wall and in the case of units 27 and 28 a removable cover is provided, indicated by the reference character of the unit supplemented by a suffix "a." In the case of mascara unit 28 a central wall 28b divides the receptacle longitudinally into a container for a body of mascara 29, and into a pocket for the related brush indicated at 31.

Rouge unit 27 contains a body of rouge 32, and the removable cover 27a normally retains a puff 33 in place upon the rouge.

Intermediate partition 12 is provided with a depending wall 37 designed as to telescope upstanding wall 17 of base 11, and is, upon its upper surface, centrally recessed to provide a shallow cup or receptacle 39, adapted to seat the usual powder retaining pad 41 and an overlying puff 42. Lid or cover 13 is slightly convex and its peripheral rim 44 engages the shouldered upper edge of intermediate member 12, so that it is retained frictionally in its closed position, as illustrated in Figure 2.

The undersides of both partition 12 and cover 13 carry reflecting mirrors, indicated by the reference characters 12b and 13b, respectively, and each is pivoted to the underlying element.

In the case of partition 12 a hinge pin 47 extends between abutments 49 on the wall 17 which at their upper ends extend into spaced recesses 48 in wall 37. The lower edge 51 of the wall 37 between abutments 49 is flattened and is so dimensioned as to abut the adjacent face of wall

17 when the partition is pivoted to its open position as illustrated in dotted lines in Figure 2. The construction holds the partition in substantially an upright position and the weight of the solid base 11 is sufficient to prevent the unit from tipping over.

The pivot pin 47 is positioned, preferably, well below the top of the base peripheral wall 17 to reduce to a minimum the turning moment present with the partition in open position.

Cover 13 for its part is pivoted to partition 12 upon a pin 53 which extends through the cover rim 44 with its ends pivotally seated in abutments 56 formed in the partition and extended into rim recesses 54. As in the case of surface 51 on wall 37 the edge surface 58 of rim 44 between the abutments 56 is so contoured that with the cover 13 pivoted upon the partition to a substantially vertical position, as shown in dotted lines in Figure 2, the surface acts as a stop to hold it upright.

Cover 13 is held against unintended displacement with respect to partition 12 by the frictional engagement of its rim 44 with the partition, as previously mentioned. Partition 12 and base 11, however, are releasably held together in the closed relationship of the device by the frictional engagement of an overhanging lip 61 on the base with the rounded edge of partition wall 37 which is somewhat thickened at 62 to provide a retaining ledge.

The use of the beauty kit constructed in accordance with the present invention is believed to be clear. In its normal closed relationship the unit is illustrated in full lines in Figures 1 and 2. Should the owner desire to use the powder in the compact, which term can be applied to the combined cover 13 and partition 12, she merely pivots the cover 13 upwardly from the partition until the stop 58 rests upon the underlying surface of the partition in which position further pivotal movement is prevented. The cover alone, pivoted to its open position, is indicated by the character A in Figure 2. She is then free to remove the puff 42 and simultaneously make use of the mirror 12b which would face her from its position on the inside of the lid 13.

Should the owner, however, desire to make use of one of the accessories positioned within the compartment formed by the partition 12 and the base 11 she would instead pivot the partition upwardly, jointly with the cover and as a unit, in which event the pivotal movement takes place about the pivot pin 47, the unit pivoting into the dotted line position B illustrated in Figure 2. When so positioned the mirror 12b on the under side of partition 12 would be presented to her view and she would be free to make use selectively of the accessories 26, 27 and 28.

As distinguished from the usual beauty kit the unit constructed in accordance with the present invention is stable with either the cover 13 pivoted to its open position or with both cover and partition 12 pivoted jointly to their open positions. The presence of the relatively great mass of solid

base 11 provides not only relatively great strength but also a balancing weight which prevents overturning under the forces exerted by the lid and/or partition in their open positions, the stops 51 and 58 preventing the pivoted elements moving into angular positions in which their turning movements would be sufficient as to unbalance the unit.

While the particular embodiment of the invention herein shown and described in detail is fully capable of attaining the objects and providing the advantages hereinbefore stated, it is to be understood that it is merely illustrative of the presently preferred embodiments of the invention and that no limitations are intended to the details of construction or design herein shown other than as defined in the appended claims.

I claim:

1. A beauty kit comprising a solid base formed with an upstanding peripheral wall and with a plurality of recessed receptacles, each including integral enclosing walls extended above the normal plane of said base, an intermediate partition pivoted to said base including a depending wall telescopically enclosing said peripheral wall of said base, a mirror affixed to the side of said partition adjacent said base, a cover pivotally connected to said partition and forming therewith a compact, a mirror affixed to the side of said cover adjacent said base, and means to retain said cover, partition and base in parallel adjacent planes.

2. A beauty kit comprising a solid base formed with an upstanding peripheral wall and with a plurality of recessed receptacles, each including an integral enclosing wall extended above the normal plane of said base, removable tops seating on said enclosing walls to close said receptacles, a recessed intermediate partition pivoted to said base including a depending wall telescopically enclosing said peripheral wall of said base, a mirror mounted on the underside of said partition, a convex cover pivoted to said partition and forming therewith a compact chamber, a mirror mounted on the underside of said cover, characterized in that said cover is pivotally secured to said partition and said partition to said base at adjacent points.
